FOREIGN PATENT DOCUMENTS

WO 2014-E50133 * 3/2014

Primary Examiner — T Chase Nelson*Assistant Examiner* — Ania Aman(74) *Attorney, Agent, or Firm* — Mitchell Ghaneie(57) **CLAIM**

The ornamental design for a pushrod top plate, as shown and described.

DESCRIPTION

FIG. 1 is a front elevational view of a pushrod top plate showing my new design;

FIG. 2 is a rear elevational view thereof;

FIG. 3 is a right side elevational view thereof;

FIG. 4 is a left side elevational view thereof;

FIG. 5 is a top elevational view thereof;

FIG. 6 is a bottom elevational view thereof;

FIG. 7 is a top isometric elevational view thereof;

FIG. 8 is a bottom isometric elevational view thereof;

FIG. 9 is a cross-sectional view taken along and in the direction of line 9-9 in FIG. 5 thereof; and,

FIG. 10 is a top isometric view of the device.

The broken lines depict portions of the environment that form no part of the claimed design.

1 Claim, 6 Drawing Sheets
